UNITED STATES PATENT OFFICE.

PATRICK CASSIDY, OF NEW YORK, N. Y., ASSIGNOR OF ONE-HALF TO I.
RICHARD ADLER, OF SAME PLACE.

PRIVY-SINK.

SPECIFICATION forming part of Letters Patent No. 331,632, dated December 1, 1885.

Application filed April 18, 1885. Serial No. 162,648. (No model.)

To all whom it may concern:

Be it known that I, PATRICK CASSIDY, a citizen of the United States, residing in the city of New York, county and State of New York, 5 have invented a new and useful Improvement in Privy-Sinks, of which the following is a specification, reference being had to the accompanying drawings, in which—

Figure 1 is a side view. Fig. 2 is a longitudinal section, and Fig. 3 is a transverse section.

A is the lower portion of the sink. B is the upper portion of the sink, inclined inwardly. C is the plug, fitting into the outlet D. a and 15 b are flanges.

Similar letters of reference indicate corresponding parts throughout the several views.

My invention relates to the construction of 20 privy-sinks adapted to the use of city schools, public buildings, tenement-houses, factories, and other buildings where, from the number and character of the occupants, the use of water-closets as usually put in dwelling-houses is rendered very undesirable, and yet where 25 the use of the old-fashioned privy-vault in the rear yard is no longer allowed by the health laws now in force in most of the larger cities.

Comparatively shallow sinks of cast-iron, forming the bottom of a privy-vault, have been 30 frequently used in the past. The vertical brick-work built from the sink upward permits water and foul matter to percolate through and saturate the ground or surrounding filling, and this vertical line of wall catches much soil 35 as it drops from the users of the privy, thus polluting the air and altogether forming a kind of construction very detrimental to public health.

My improvement consists in making the 40 portion above the sink proper to incline inwardly, so as to avoid the soil dropping or lodging on the sides of the privy. I make the lower portion, (the sink, A,) of proper width and shape, and having a proper outlet, D, and 45 fitted with a suitable overflow-plug, C. The sink A is provided with a surrounding flange, a. Above the sink A, I place the inwardly-inclined extension B, which in the accompa-

nying drawings is represented of cast metal, and provided with a surrounding flange, b, so 50 that the extension or upper portion can be bolted to the lower portion, making a watertight joint with the help of putty, or in other ways well known to plumbers and workers in iron. The length of these privy-sinks will 55 vary according to the number of persons they are intended to accommodate at one time. The extension or upper portion may therefore be in one entire casting for the shorter lengths, or may be made up in a number of pieces properly put together for the longer lengths. While I prefer to make the inwardly-inclined sides, as described, of cast-iron, on account of economy and durability, such sides may be made of other metals or of slate, stone, burned clay, 60 or any other suitable material.

The privy-sink A is placed a suitable distance down into the ground, with the inwardly-inclined extension B connected together, and above this latter portion is arranged the 70 usual wooden seats. A suitable amount of water is let into the sink, and daily or oftener the soil is let off by raising the plug. The upper portion, B, from its inclined lines will not only be free from liability to catch the 75 dropping soil, but its smooth hard surface can be readily cleaned with a broom in case any filth is lodged upon or thrown against it.

The entire construction will be water-tight, so that all saturation of the surrounding earth 80 will be prevented. The lodgment of soil above the water-line will be avoided, and therefore merits approval from a sanitary standpoint.

What I claim, and desire to secure by Letters Patent of the United States, is— 85

A privy-sink divided horizontally at or near its center into an upper and lower portion, flanged and bolted together, forming a watertight trough having its contracted upper side open for its entire length, substantially as 90 shown, and for the purpose specified.

PATRICK CASSIDY.
